DIE CASTING MACHINE

Alfred F. Jelinek, Cleveland, Ohio, assignor to The
Cleveland Automatic Machine Company, Cleve-
land, Ohio, a corporation of Ohio

Application January 18, 1947, Serial No. 722,871

2 Claims. (Cl. 22—92)

1

This invention relates generally to die casting machines of the horizontally movable die type and more specifically to improvements in the support for the die plates therein.

In die casting machines of the foregoing type, the die parts are supported upon two heavy rigid vertical plates, one of which is stationary during operation of the machine, the other of which is mounted for retraction relative thereto in order to facilitate separation of the dies. It is customary in machines of this character to support the movable plate on a plurality of guide bars disposed in parallel relation to the bed of the machine and mounted adjacent the opposed ends thereof. In prior art devices difficulty has been encountered in maintaining alignment of the two die members due to the deflection of the guide bars under the combined weight of the die and movable plate. In many instances, the guide bars have been bowed to such extent as to inhibit registration of the die parts or intimate engagement of the mating faces thereof.

The primary object of this invention resides in the provision of a structure which will assure alignment of the die parts at all times throughout the life of the machine. To this end, the movable die plate is constructed so that the major portion of the weight thereof is imposed upon the bed of the machine and the guide bars are relieved from any function other than that of maintaining the movable die member in aligned relation with its companion part.

Another object of the invention is to provide a support for the movable die parts which will facilitate adjustments thereof to compensate for wear or the replacement of worn parts without dismantling the movable plate assembly.

A further object of the invention resides in the provision of a load supporting structure that may be readily interposed between the bed and movable die plate in machines of a like character.

Other objects and advantages more or less ancillary to the foregoing and the manner in which all the various objects are realized will appear in the following description, which considered in connection with the accompanying drawings, sets forth the preferred embodiment of the invention.

In the drawings:

Fig. 1 is a side elevation of the improved die casting machine illustrating the major elements thereof;

Fig. 2 is a section taken on the line 2—2 of Fig. 1 showing a general arrangement of the toggle mechanism;

2

Fig. 3 is a section taken on the line 4—4 of Fig. 1 showing the improved rod supporting structure embodying the present invention;

Fig. 4 is a fragmentary section through one of the improved rod supporting assemblies; and

Fig. 5 is a perspective view of one of the adjusting wedge blocks.

One die casting machine within which the improved supporting structure may be incorporated is described in U. S. Patent No. 2,334,372, issued to Abbott et al. on November 16, 1943. The present invention is illustrated and described as applied to the machine of the aforesaid patent though certain structural details thereof, which are not directly pertinent to the improved support, have been omitted herein.

The bed 10 of the machine is preferably constructed from fabricated sheet steel members 11 having ways 12 mounted thereon. The forward end of the machine is provided with a stationary die supporting plate 13 which cooperates with the movable die supporting plate 14 to support the die parts D. The opposed end of the machine is formed with a second stationary plate 15, both of the stationary plates being bored adjacent the corners thereof for the support of guide bars 16. The die plate 14 is apertured for sliding engagement upon the bars and is preferably provided with elongated bosses 17 circumambient the bores to increase the wearing surface and assure the stability of the plate. A toggle mechanism 20 is provided to effect the reciprocation of the die plate 14 and hold the die parts in impinged relation with each other during the casting operation. The toggle mechanism is actuated by push rod 21 connected to a piston and cylinder assembly of conventional form. Admission of fluid alternately to one or the other end of the cylinder advances or retracts the movable die plate at the proper time during the operating cycle of the machine. To this end, a pump 22, driven by a prime mover, (not shown) supplies fluid under pressure through a control valve 23 and conduits 24 to the cylinder as required. The ways 12 are formed with T-slots 27 (Figs. 3 and 4) for the reception of T-headed bolts 28 mounted in the base of the plates 13 and 15.

As described in the Abbott patent referred to above, it is customary to provide a cylinder 29 having a piston therein for actuating a plunger in the molten metal supply system to inject molten metal under pressure into the die cavities. Cylinder 29 may be adjustably mounted on a pair of rods 25 as described in the aforesaid Abbott patent, the details of the mounting forming

to part of the invention. A blower, furnace and melting pot, housed within a chamber 30, are provided to reduce the metal to a molten state. The latter parts are not shown in detail herein since they form per se no part of the present invention. The cylinder 29 is connected by suitable conduits 32 to control valves 33 indicated schematically in Fig. 1. A tank 34 containing liquid under the pressure, such as nitrogen, is customarily employed for actuating the piston in the cylinder 29. When the control valves 33 are operated at the proper time during the operative cycle of the machine, the piston in the cylinder 29 effects the rapid injection of a metered amount of molten metal into the die cavities.

In order to relieve the guide bars 16 of part or all of the load except that exerted in the exercise of their guiding function, the upper faces of the central portions of the ways 12 have secured thereto by means of screws 39 a pair of hardened wear plates 40 which are disposed in a common horizontal plane and surface ground parallel to the axis of the guide bars 16. As illustrated in Figs. 3 and 4, the base of the movable die plate 14 is formed with inclined corners 41 which are engaged with bronze saddles or supporting blocks 42, having flat bottom surfaces for sliding engagement with the wear plates 40 and upper inclined surfaces 43 congruent to the associated surfaces 41 in the die plate. The vertically disposed ears or side walls 47 (Fig. 5) of the blocks are formed for abutting engagement with the opposed faces of the plate in order to effect the retention of the blocks against longitudinal displacement during the reciprocative movement of the plate.

The forward face of each block 42 is tapped for the reception of cap screws 44 for the support of a plate 45 having a clearance hole in the central portion thereof to receive a draw bolt 46 threaded in side wall of the die plate 14. With this structure, the draw bolts 46 may be adjusted until die plate is suitably elevated to relieve the load upon the guide bars and permit the plate to move freely thereover. Obviously, if the blocks are adjusted too far inwardly, the die plate 14 will bear against the bottom of the guide bars and undesirable wear and binding will occur. Likewise, if the blocks are withdrawn too far, the weight of the die plate will be imposed upon the guide bars and will cause them to sag or bow characteristic of the prior art devices. In the initial construction of the machine, dial indicators may be employed to measure height and parallel relation between the guide bars and the hardened plates 40. A like procedure may be followed thereafter in adjusting the blocks, the dial indicators or other measuring instruments being used in this case, however, to check the deflection of the bars 16. With this construction, the guide bars serve to perform the function of dowels rather than load carrying members; hence, the die members will be maintained in aligned relation with each other and the parting line marking on the die castings will be minimized. The wear plates 40 may be removed, replaced or resurfaced if objectionable wear is encountered. Being of simple, easily-machined construction such replacement or resurfacing may be done economically.

Having described in detail one embodiment of the present invention, it will readily be recognized that a simple, yet highly effective structure, has been provided to convert the action of the somewhat erratic machines of the prior art into a machine which is dependable, accurate and capable of maintaining alignment of the die members, irrespective of wear.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

What I claim is:

1. In a die casting machine, a bed, a stationary die plate supported by said bed, a bracket supported by said bed, guide rods supported by said die plate and bracket, a movable die plate slidably mounted on said guide rods, wear plates having a flat upper surface, means removably mounting said wear plates on said bed for slidably supporting said movable die plate, and shoe means mounted on said movable die plate for engaging said wear plates to relieve said guide rods of the weight of the movable die plate, said shoe means being adjustable to increase the effective vertical dimension thereof so that the apportionment of the load supporting function between the guide rods and the wear plates may be controlled.
2. In a die casting machine, a bed, a stationary die plate supported by said bed, a bracket supported by said bed, guide rods supported by said die plate and bracket, a movable die plate slidably mounted on said guide rods, a pair of wear plates having flat upper surfaces formed on said bed for slidably supporting said movable die plate, means removably attaching said wear plates to the bed, there being a beveled bearing surface formed on opposite sides of said movable die plate, and beveled shoe means on said movable die plate for engaging said wear plates to relieve said guide rods of the weight of the movable die plate, said shoe means being adjustable to increase the effective vertical dimension thereof so that the apportionment of the load supporting function between the guide rods and the wear plates may be controlled.

ALFRED F. JELINEK.
